Emerson R. Newell

UNITED STATES PATENT OFFICE.

ALBERT E. BERDON, OF DETROIT, MICHIGAN, ASSIGNOR TO DODGE BROTHERS, OF DETROIT, MICHIGAN, A CORPORATION OF MICHIGAN.

OIL-PAN HEATER.

1,391,040.

Specification of Letters Patent. Patented Sept. 20, 1921.

Application filed July 29, 1920. Serial No. 399,800.

To all whom it may concern:

Be it known that I, ALBERT E. BERDON, a citizen of the United States, residing at Detroit, Michigan, have invented certain new and useful Improvements in Oil-Pan Heaters, of which the following is a clear, full, and exact description.

My invention relates to oil pan heaters for use in internal combustion engines, and particularly with automobile engines, the object being to simplify and improve the construction of such devices.

An important feature of the invention consists in the provision of an oil pan heater extending into the oil pan from one side only. Other features and advantages will become apparent from the following detailed description and claims when taken in connection with the accompanying drawings, in which—

Figure 1 is a view showing portions of an engine and means for attaching my heater to the oil pan thereof; and

Fig. 2 is a sectional view on the line 2—2 of Fig. 1.

Referring to the drawings, the oil pan 1 may, and preferably does form part of the crank casing, and near the bottom thereof is secured a casting 2 riveted to the bottom of the oil pan at 3. This casting provides a seat for an elbow 4, which is attached to the end of the flexible tube leading from the exhaust manifold. The elbow 4 and casting 2 are properly faced off, and a copper and asbestos gasket 5 is interposed between them so as to make a joint that will not leak. The elbow 4 carries the oil heater proper, said heater consisting of an outer tube 6 and an inner tube 7, the outer tube being closed at its inner end and open at its outer end, the inner tube being open at both ends so that the gases may flow into the outer tube across the bottom of the oil pan heater and back through the inner tube 7 from which they pass into the atmosphere at its outer opening 8.

A flexible tube 9 is fastened to the elbow 4 and leads to the exhaust manifold 10. The valve 11 is provided in the tube 9, which

valve may be controlled from the instrument board by means of a Bowden wire 12 inclosed in a casing 13. The wire 12 is connected at the instrument board 15 to a button 14, and when pushed in, the valve is opened so as to allow the exhaust gases to flow into the oil pan heater.

The usual screen 16 is provided and, as shown, lies near the heater and is inserted from the opposite side thereof.

While I have described the preferred form of my invention, it is obvious that variations may be resorted to within the scope thereof, and that parts may be used without others.

Having thus described my invention, what I desire to claim and secure by Letters Patent is—

1. An oil pan heater adapted for use in internal combustion engines, said heater having inlet means for the heating gases, and outlet means for the same, said means being situated one within the other.

2. An oil pan heater adapted for use in internal combustion engines, said heater having an outer shell and an inner shell, the outer shell being closed at its inner end and connected with the heat supply at its outer end, the inner shell having an open end terminating short of the inner end of the outer shell, the outer end of the inner shell being open to the atmosphere.

3. An oil pan heater adapted for use in internal combustion engines, said heater having an outer shell and an inner shell, the outer shell being closed at its inner end and connected with the heat supply at its outer end, the inner shell having an open end terminating short of the inner end of the outer shell, the outer end of the inner shell being open to the atmosphere, and a valve controlling a supply of heat to said outer shell.

Signed at Detroit, Michigan, this 19th day of July, 1920.

ALBERT E. BERDON.
